UNITED STATES PATENT OFFICE

FLOYD M. OVERBEY, OF LEAVENWORTH, KANSAS

CHAIR

Application filed January 25, 1929. Serial No. 335,066.

This invention relates to an article of furniture of the nature of a chair, or settee, and provides a device of this nature which is both convertible and foldable and adapted for use with or without rockers, and which may be reduced to compact form for convenience of handling and storing.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which:—

Figure 1 is a perspective view illustrating an embodiment of the invention and showing the article as it appears when adjusted for use.

Figure 2 is a side view showing the chair folded.

Figure 3 is an enlarged fragmentary sectional view of a rocker and the member pivoted thereto.

Figure 4 is an enlarged detail sectional view of a portion of the rocker and the member having interengaging connection therewith.

Corresponding and like parts are referred to in the following description and designated in the several views of the drawing by like reference characters.

The chair or analogous article comprises members 1 and 2 which cross and are pivotally connected at the point of crossing, as indicated at 3. There are two sets of members 1 and 2 which are transversely spaced apart a distance corresponding to the width or length of the article. The members 1 are approximately double the length of the members 2 and form elements of the back. An upper cross member 4, a lower cross member 5 and intermediate cross members 6 and 7 connect the side members 1. Rods 8 connect the cross pieces 4 and 6 and form the

back. Arms 9 are pivoted at their rear ends to the side members 1 and are supported in horizontal position by means of braces 10. A strip 11 depends from each of the arms 9 and has a longitudinal slot 12 formed therein to receive the fastenings 13 by means of which upper ends of the braces 10 are slidably connected with the arms to admit of the compact folding of the structure, as indicated most clearly in Figure 2 of the drawing.

A seat 14 is pivotally connected adjacent its forward edge with the upper ends of the members 2, as indicated at 15. The rear portion of the seat 14 is slidably connected with the side members 1.

A groove 16 is formed in the inner side of each of the members 1 and receives a pin or other element projecting laterally from the rear portion of the seat.

Rockers 17 are provided and are detachably fitted to the lower ends of the members 1 and 2, thereby admitting of the article being used with or without rockers as required. The lower ends of the members 1 and 2 are received in mortises formed in the top side of the rockers 17. Screws or like fastenings 18 pivotally and detachably connect the members 1 with the rockers 17. Plates 19 applied to opposite sides of the rockers 17 reinforce and strengthen the same opposite the mortises provided to receive the lower ends of the members 1. The lower end of each of the members 2 is offset to form a shoulder 20 which engages under the metal strap 21 extending over and along opposite sides of the rocker 17 adjacent the mortise formed therein to receive the lower end of the member 2. The lower end of each of the members 2 is reinforced by a metal strap 22. When the chair is set up for use the shoulders 20 of the members 2 engage under the overhanging portion of the strap 21 thereby retaining the parts in position. When folding the chair the rear end of the seat 14 is moved upwardly. This results in a pivotal movement of the members 2 which withdraws their lower ends from engagement with the overhanging portions of the strap 21, thereby admitting of the folding of the

chair.

chair in the manner substantially as indicated in Figure 2 of the drawing, whereby it occupies a minimum space for convenience of handling and storing.

5 Having thus described the invention, I claim:—

A chair or analogous article of furniture comprising side members crossing and pivotally connected at the point of crossing, 10 the rear members being extended to form supporting elements for the back and having longitudinally disposed grooves in their inner sides, a seat pivotally connected to the upper ends of the front members and slidably connected with the upper portion of the rear members through the instrumentality of the grooves thereof, arms pivoted at their rear ends to the upper portions of the rear members, longitudinally slotted strips depending from the arms and braces pivoted at their lower ends to the lower ends of the rear members and slidably connected at their upper ends to the strips depending from the arms.

25 In testimony whereof I affix my signature.
